ROTARY PUMP

Walter Czarnecki, Eddington, Pa., assignor to Eddington Metal Specialty Co., Eddington, Pa., a firm composed of Walter Czarnecki, Sr., Mary Czarnecki, Nellie Wojsowski, Wesley Czarnecki, Stanley Czarnecki, Walter V. Czarnecki, Jr., and Casimer Czarnecki

Application October 11, 1937, Serial No. 168,336

3 Claims. (Cl. 103—136)

This invention has to do with rotary pumps of the type commonly employed for the purpose of building up pressure in a fluid fuel that is used with oil burners.

5 This application is a continuation in part of the co-pending application of Walter Czarnecki, Serial No. 133,131, filed March 26, 1937, and entitled "Fuel supply unit."

10 The present invention has in view as its foremost objective the provision of a rotary pump of a highly improved nature in which a rotor is eccentrically mounted in the cylindrical bore of a housing and which rotor is formed with radial slots in which are positioned vanes. These vanes 15 are designed to be maintained in engagement with the cylindrical bore of the housing and thus slide in the slots as the rotor rotates.

A particular feature of the invention lies in the provision of novel means for causing the movement of the vanes in the slots in the rotor.

20 Yet another object of the present invention is the provision of a rotary pump of the type above identified in which the vanes take the form of cylindrical rollers, and the slots in which the vanes are received are formed with bottoms that have a curvature complementary to that of the rollers. With this arrangement, friction between the vanes and the cylindrical bore of the housing is reduced to a minimum without a loss in the pressure building-up effects.

25 Another object of the invention is to provide, in a rotary pump of the character above noted, novel means for effecting a seal whereby escape of fluid from the bore in which it is affected by the vanes is prevented.

30 Various other more detailed objects of the invention will in part become apparent and in part be hereinafter stated as the description of the invention proceeds.

The invention, therefore, comprises a rotary pump including a pump housing having a cylindrical bore in which a rotor is eccentrically mounted, and the rotor is provided with radial slots in which vanes are positioned. Novel means 40 for causing movement of the vanes in the slots to maintain the vanes in engagement with the cylindrical wall of the bore are provided.

An important feature of the invention is the cylindrical shape of the vanes and the complementary shape of the slots in which they operate.

45 For a full and more complete understanding of the invention reference may be had to the following description and accompanying drawings, wherein

Figure 1 is a longitudinal section through a

housing of a rotary pump made in accordance with the precepts of this invention.

Figure 2 is an enlarged detailed showing taken as a section at right angles to the showing of Figure 1, bringing out the disposition of the rotor in the housing.

Figure 3 is a view somewhat similar to Figure 2 developing the end rings for the rotor vanes therein.

Figure 4 is a view similar to Figure 2 of the 10 modification in which the vanes take the form of cylindrical rollers.

Figure 5 is a detailed sectional view taken at right angles to the showing of Figure 4.

Figure 6 is a detailed elevational showing of 15 one of the end rings for the modification of Figures 4 and 5.

Figure 7 is a view somewhat similar to Figure 1 of a modified form.

Figure 8 is a detailed view in elevation of the 20 shaft and rotor carried thereby shown in Figure 7.

Figure 9 is a view developing the elements of the assembly at the end of the shaft of the modification shown in Figure 7 in an exploded relationship, and

Figure 10 is an exploded view somewhat similar to Figure 9 of the packing arrangement at the other end of the shaft.

Referring now to the drawings, wherein like reference characters denote corresponding parts, 30 the housing for the rotary pump of this invention is referred to in its entirety by the reference character B. This housing B may be made from any appropriate metal which is machined to accommodate the various mechanisms which are carried thereby and other organizations which are intended to be attached thereto. The main body member B is formed with a circularly shaped portion 10 which is reduced in diameter as indicated at 11, and the portion 11 is further reduced in diameter as shown at 12, the reduced portion 12 being provided with threads designated 13. Extending throughout the portion 10 is a circular opening or bore 14 which terminates in the shoulder represented at 15. From the shoulder 15, through the portions 11 and 12, is a circular recess 16, the axis of which is out of alignment with the axis of the bore 14. In other words, the circular recess 16 is eccentric to the bore 14.

45 The wall of the portion 10 is formed with an opening 17 which is shown in Figure 2 and which establishes communication between the bore 14 and the source of supply of fluid which is to be affected by the pump.

50

A passageway designated 18 extends from the bore 14 to any appropriate point such as the pressure regulating valve illustrated and described in the above identified co-pending application. 5 This passageway 18 extends through a flange 19 which constitutes a means for securing a pressure regulating valve in position on the main body part B.

An end closure for the bore 14 is shown at 20, 10 and this end closure is formed with an extension 21 which extends into and snugly fits within the bore 14. This end closure 20 may be secured in position on the main body part B by the headed screw bolts 22, which extend through openings 15 in the end closure 20 and are screwed into threaded sockets 23 in the main body part B.

The end closure 20 is provided with a cylindrical socket 24 which is eccentric to the axis or 20 the bore 14, that is the axis of the socket 24 constitutes a continuation of the axis of the cylindrical recess 16. Thus, the axes of the socket 24 and recess 16 are in alignment.

A bushing designated 25 has an outer cylindrical surface which is snugly received in the bore 14. It is important to note that the bushing 25 is provided with a cylindrical bore 26, the axis of which is in alignment with the axes of the socket 24 and circular recess 16.

A shaft referred to in its entirety by the reference character S is shown as having one end 30 received in the socket 24 whereby the latter is constituted a bearing for the shaft. This shaft has an enlarged portion at 27 which is received in the bore 26 so that the bearing 25 constitutes a bearing for the shaft S.

In order to prevent longitudinal movement of the shaft S the latter is formed with a flange at 28 and which flange is received in a cut-away portion of the bushing 25 that is shown at 29.

40 An end bushing designated 30 is fitted in the end of the circular recess 16 within the reduced portion 12, and this bushing 30 is provided with an end flange at 31 which engages the end of the reduced portion 12.

45 A cup member 32 has an inner cylindrical wall which is threaded as shown at 33, and this threaded wall 33 is secured onto the threads 13 of the reduced portion 12. The cup member 32 has a bottom 34 which is formed with an opening 50 35, the axis of which is in alignment with the axis of the circular recess 13. A bearing member 36 is received in a socket 37 which is formed in the bushing 30 and this bearing member 36 has a central bore 38 through which passes the 55 shaft S.

A packing assembly is referred to in its entirety at P¹ and is effective to provide a seal between the shaft S and the bushing 30. Another packing assembly P² provides a seal between the 60 shaft S and the bushing 25. A coil spring shown at 39 extends between the packing assemblies P¹ and P², respectively, and maintains these packing assemblies in effective position against the bushings 30 and 25.

65 A similar arrangement for providing seals at similar points in a rotary pump of the same type is clearly illustrated and described in the co-pending application of Walter Czarnecki, et al., Serial No. 85,908, filed June 13, 1936, entitled "Pump," and the specification of this patent application is referred to for a detailed description of these packing assemblies.

A passageway is shown at 40 as extending 75 lengthwise through the bushing 25 and is present

for drainage purposes as will hereinafter be described.

Keyed to the shaft S between the end closure 20 and bushing 25 is a rotor designated 41; a driving relationship between the rotor 41 and shaft S being established by the key shown at 42. The rotor 41 has an outer cylindrical surface designated 43, in which are cut a plurality of slots 44, the side walls of which are parallel to radii of the rotor, which radii extend between the walls of each slot 44.

Slidably received in each of the slots 44 are vanes 45 which extend at each end beyond the rotor 41. Disposed between the rotor 41 and end closure 20 is an end ring member 46 which end ring member is brought out clearly in Figure 3. This end ring member is duplicated at the other end of the rotor 41 whereat it is positioned between the extremities of the rotor 41 and bushing 25. Each of the ring members 46 has an outer periphery 47 which is snugly received in the bore 14, and extending inwardly from this peripheral edge 47 are a plurality of slots 48 which correspond to the slots 44 in the rotor 41. However, it is notable that each of the slots 48 is wider than the corresponding slot 44, and each of the slots 48 has side edges which are parallel to radii of the bore 14, which radii extend between the walls of the respective slot.

The vanes 45 at each end extend into the 30 slots 48, as shown in Figures 1 and 3, and due to the slots 48 being wider than the vanes 45, a small amount of relative movement between the extremities of the vanes in these slots 48 in the ring 46 is provided for. It is notable that each 35 vane 45 at all times is in engagement with the bore 14 on its outer edge, and the end portions on the inner edge engage with the bottoms of the slots 48 in the rings 46 at each end.

Provision is made for driving the shaft S in 40 any preferred manner, as indicated by the flat 49, and when the shaft S is rotated a corresponding rotation is set up in the rotor 41. Due to the engagement of the end portions of the vanes 45 with the bottoms of the slots 48 each 45 of the vanes 45 will be maintained in an outermost position with the edges of the vanes 45 in engagement with the bore 14. Due to the eccentricity existing between the axes of the rotor and the bore 14, respectively, the bore 14 will 50 be effective to force the vanes inwardly in the slots 44 incident to the rotation of the rotor 41.

Assuming that the rotor 41 is rotated in a counterclockwise direction with respect to the showing in Figure 2, it is notable that fluid passing through the openings 17 will enter into the space between the rotor 41 and the bore 14. The vanes 45 being in their outermost positions with the edges engaging the bore 14 will affect the fluid to build up pressure therein as the shaft 60 is rotated, so that fluid under increased pressure is delivered to the passageway 18.

This sliding movement of the vanes 45 in the slots 44 of the rotor 41 is accommodated by the breadth of the slots 48 in the end rings 46; the 65 action of the extremities of the vanes in these slots 48 of the ring 46 being brought out clearly in Figure 3.

As the space between the bore 14 and cylindrical surface 43 of the rotor 41 decreases, speaking with reference to a counter-clockwise direction of the showing of Figures 2 and 3, the pressure of the fluid in this space will obviously increase and at the same time the extremities of the vanes 45 in the slots 48 will move from one 75

wall of the slot over to the other, so at the time of maximum pressure on the fluid, which is just at or prior to the time of being forced into the passage 18, the surface of the vane which is forced against the fluid to build up the pressure will be in engagement with the side walls of the slots 48 as shown at 50 in Figure 3.

While the vane and associated pump structure illustrated in Figures 1, 2 and 3 is designed with the vanes and slots of a rectangular cross sectional shape, it is not essential that the vanes be so formed. It is notable that the term "vanes" as used throughout this specification is intended to refer to vanes of any shape having the required ability to affect the fluid to build up pressure therein incident to rotation of the rotor in the manner illustrated.

Figures 4, 5 and 6 develop a slightly modified form in which the vanes 51 are cylindrical in shape and operate in complementally shaped slots 52 formed in the rotor 41. Each of the end rings 46a will also be formed with similarly shaped notches 53 which are designed to accommodate the cylindrical vanes 51.

25 In actual use the cylindrical blades 51 will probably present a noticeable advantage inherent to their cylindrical formation and mounting which permits them to turn freely. As the rotor 41 is rotated these cylindrical blades 51 will 30 roll over the surface of the bore 14 with a minimum resistance to turning of the rotor.

Despite the presence of the packing assembly P² a certain amount of the fluid fuel being operated on by the pump may escape into the space 35 defined by the circular recess 16. In order to provide for the return of this fluid to the bore 14 the bushing 25 is provided with the channel 40 which is inclined and opens at its upper end into the pumping chamber defined by the bore 40 14 and rotor 41. At its lower end the channel 40 opens into the circular recess 16. As the rotor 41 is rotated a certain amount of suction or partial vacuum is created to draw fluid from the recess 16 and pass it into the pumping chamber 45 of the bore 14.

Referring now more particularly to Figures 7, 8, 9 and 10 the shaft S is shown as being of a different construction which makes possible the elimination of the seals P¹ and P² and the substitution of a highly simplified assembly for accomplishing the same sealing purposes. This shaft S is formed with the usual enlarged portion at 27 which is received in the bearing 25. However, the end wall of the bearing 25 which 55 is disposed towards the rotor is formed with a ring-like groove 70 in which is fitted a sealing ring 71.

Adjacent the enlarged portion 27 of the shaft S the latter is further enlarged to provide a ring-like flange 72 that bears against the sealing ring 71 and serves to maintain the latter seated in the groove 70. Adjacent to the ring flange 72 the shaft S is reduced in diameter, and keyed thereon is a rotor 73 which is formed with spirally disposed grooves 74 in which operate rotor vanes 45a in the manner above described. It is notable, however, that these rotor vanes 45a will have a shape corresponding to the grooves 74. End ring members 46b may be positioned at each side of the rotor 73 in a manner corresponding to the arrangement illustrated in Figure 1. Due to the spiral formation of the vanes 45a and groove 74 the notches 48b in the 75 end rings 46b must be sufficiently wide to receive

the extremities of the vanes and allow for lateral play incident to rotation of the rotor 73.

It is notable that rotation of the rotor 73 in a proper direction causes the vanes to affect the fluid to urge the latter in the direction of 5 the ring flange 72, thus creating a tendency to urge this flange 72 against the sealing ring 71 to maintain the sealed relationship.

This pressure which is afforded by the fluid during operation of the pump is supplemented 10 to a required extent by an assembly now to be described. The end of the shaft S is formed with a depression 75 that partially receives a ball bearing element 76. This ball bearing element 76 is also partially received in another depression 77 that is formed in a bearing member 78 that is provided with a stud 79. Positioned about the stud 79 and bearing against the member 78 is a coil spring 80 which at its other extremity receives a stud 81 formed on a bearing element 82. This bearing element 82 is formed with a conical depression 83 in which is fitted the complementally shaped point of a set screw 84. This set screw 84 is screwed in a threaded bore 85 of a plug member 86, the threaded bore 25 85 being closed by a screw plug 87.

An end closure 88 replaces the end closure 20 and is formed with a portion 89 that is comparable to the portion 24 of the end closure 20. This extension 89 projects into the bore 14 in 30 a manner above described. However, the end closure 88 differs materially from the end closure 20 in that it is formed with a sleeve-like extension 90 which is provided with a bore 91 that extends through the end closure including the 35 extension 89. This bore 91 is threaded at one end as shown at 92, to receive the plug 86. At its inner end the bore 91 receives the extremity of the shaft S.

It is evident that the spring 80 exerts pressure 40 on the shaft S through the bearing members 78 and 76 to urge the ring flange 72 against the sealing ring 71, and this tension may be varied by first taking out the screw plug 87 to afford access to the set screw 84. By using an 45 appropriate tool this set screw may be tightened up or released as occasion demands, to vary the tension afforded by the spring 80.

Referring now more particularly to the sealing arrangement at the other end of the shaft S, it 50 is noted that one part of a packing gland assembly designated 93 is snugly received in the bore 16 and is formed with a bore 94 that receives the shaft S. This member 93 has an end flange 95 that engages the housing B. 55

The member 93 is formed with a packing chamber 96 that surrounds the shaft S and the end portion of the wall of the member 93 which defines the chamber is threaded as shown at 97. An appropriate packing material such as felt is 60 shown at 98 as being packed in the chamber 96; the required pressure being set up by a packing gland 99 that is threaded into the threaded wall 97.

A lock nut shown at 100 is screwed on to the 65 packing gland 99 and serves to lock the same in any adjusted position. From the foregoing it is apparent that the seal P¹ is replaced by the packing gland just previously described, whereas the packing assembly P² is obviated and its sealing 70 functions replaced by the sealing ring 71 and flange 72 that is formed as a part of the shaft S.

While preferred specific embodiments of the invention are hereinbefore set forth it is to be clearly understood that I am not to be limited to

the exact constructions illustrated and described, because various modifications of these details may be provided in putting the invention into practice within the purview of the appended 5 claims.

I claim:

1. A rotary pump of the character described comprising a main body part formed with a bore, said main body part having an extension formed 10 with a bore that is eccentric to the bore in the main body part, a shaft extending through the said bores, the shaft being eccentrically mounted with respect to the bore in the main body part, a packing assembly located at the free end 15 of the extension for effecting a seal about the shaft, a bushing in the extension adjacent to the main body part, said bushing being interposed between the shaft and the wall of the extension defining the bore, said bushing being formed with 20 a groove on the face adjacent to the main body part, a sealing ring in said groove, the shaft being formed with a ring-like flange engaging said sealing ring, a rotor drivably carried by the shaft and disposed in the bore of the main body part, 25 said rotor having a plurality of spirally disposed grooves, and correspondingly spiralled vanes in said grooves.

2. A rotary pump of the character described comprising a main body part formed with a bore, 30 said main body part having an extension formed with a bore that is eccentric to the bore in the main body part, a shaft extending through the said bores, the shaft being eccentrically mounted with respect to the bore in the main body 35 part, a packing assembly located at the free end of the extension for effecting a seal about the shaft, a bushing in the extension adjacent to the main body part, said bushing being interposed between the shaft and the wall of the extension defining the bore, said bushing being formed with a groove on the face adjacent to the main body part, a sealing ring in said groove, the shaft being formed 40 with a ring-like flange engaging said sealing ring, a rotor drivably carried by the shaft and disposed in the bore of the main body 45

part, said rotor having a plurality of spirally disposed grooves, correspondingly spiralled vanes in said grooves, end rings for causing radial movement of the vanes with respect to the rotor, an end closure for the bore in the main body 5 part, said end closure being formed with a passageway that receives the extremity of the said shaft, and means carried by the end closure for exerting a pressure on the shaft whereby the ring flange is urged against the sealing ring. 10

3. A rotary pump of the character described comprising a main body part formed with a bore, said main body part having an extension formed with a bore that is eccentric to the bore in the main body part, a shaft extending through the 15 said bores, the shaft being eccentrically mounted with respect to the bore in the main body part, a packing assembly located at the free end of the extension for effecting a seal about the shaft, a bushing in the extension adjacent to the main 20 body part, said bushing being interposed between the shaft and the wall of the extension defining the bore, said bushing being formed with a groove on the face adjacent to the main body part, a sealing ring in said groove, the shaft being formed 25 with a ring-like flange engaging said sealing ring, a rotor drivably carried by the shaft and disposed in the bore of the main body part, said rotor having a plurality of spirally disposed grooves, correspondingly spiralled vanes in said grooves, 30 end rings for causing radial movement of the vanes with respect to the rotor, an end closure for the bore in the main body part, said end closure being formed with a passageway that receives the extremity of the said shaft (a spring 35 in the passageway of the end closure, a bearing assembly interposed between one end of the spring and the end of the shaft, a bearing member associated with the other end of the spring, a plug for the passageway and the end closure, and an adjustable set screw threaded in the plug 40 engaging the last mentioned bearing member and operable to vary the tension afforded by the spring.

WALTER CZARNECKI.

45
